UNITED STATES PATENT OFFICE.

FRANK A. SCHRAMM AND AMBROSIUS MODERY, OF PHILADELPHIA, PA.

PIPE-WRENCH.

SPECIFICATION forming part of Letters Patent No. 295,204, dated March 18, 1884.

Application filed December 7, 1883. (No model.)

To all whom it may concern:

Be it known that we, FRANK A. SCHRAMM, a subject of Bavaria, having resided one year last past in the United States, and made oath of intention to become a citizen thereof, and AMBROSIUS MODERY, a subject of Baden, both residents of the city and county of Philadelphia, State of Pennsylvania, have invented a new and useful Improvement in Pipe-Wrenches, which improvement is fully set forth in the following specification and accompanying drawings, in which—

Figure 1 is a partial side elevation and partial section in line *x x*, Fig. 3, of a wrench embodying our invention. Fig. 2 is a partial side elevation and partial section in line *y y*, Fig. 3. Fig. 3 is a partial side elevation at a right angle to Figs. 1 and 2, and partial section in line *z z*, Fig. 2.

Similar letters of reference indicate corresponding parts in the several figures.

Our invention consists of improvements in wrenches, as will be hereinafter fully set forth and definitely claimed.

Referring to the drawings, A represents the handle of the wrench, and B the stationary jaw, which is formed with said handle.

C represents the movable jaw, which, overhanging the stationary jaw, is pivoted to the base of the stationary jaw, and has its pivotal end fitted in a recess, *a*, in said stationary jaw, the recess being extended, as at *a'*, to permit the play of the shank portion of the movable jaw. The biting-face *b* of the stationary jaw is elliptical, and that, *c*, of the movable jaw is recessed in V form, so as to form a deep seat for the pipe or other article to be grasped, and said biting-faces are serrated, the serrations of the two faces extending in reverse directions.

D represents the pivotal bolt of the jaw C, the same being squared at the center of its length to enter a squared opening in said jaw, and the portions on opposite sides of the jaw are cylindrical and enter cylindrical openings in the base of the stationary jaw, whereby the movable jaw is readily permitted to rotate. The ends of the bolt are extended beyond the sides of the jaw B, and to said ends

are connected coiled springs E, which are also connected with the stationary jaw, whereby the power of said springs is exerted on the movable jaw so as to force the same toward the stationary jaw.

On the ends of the bolt D are caps F F', of dishing form, which inclose the springs E, thus protecting and concealing the same and preventing contact of the hands therewith. With one end of the bolt is formed the cap F, and with the other end is connected the cap F', the connection being accomplished by heading or riveting said end flush with the cap. Should the end be projected beyond the cap, it may be threaded for engagement of a nut, it being seen that the caps abut against the opposite sides of the stationary jaw, and turn thereon; and, being fixed to the bolt, prevent displacement thereof.

It will be seen that when the wrench is presented to the pipe, &c., to be grasped, as shown by the dotted figure at the left hand of the jaws in Figs. 1 and 2, and the wrench is forced against the pipe, the movable jaw yields and opens the space between the same and the stationary jaw until the pipe is enabled to enter the recess *c*, the movable jaw then closing on the pipe and forcing it against the face *b*. By operating the wrench the bite of the jaws is powerfully increased, and the pipe thereby forcibly grasped and readily turned by the wrench. By operating the wrench in reversed direction the jaws ride freely over the pipe, and are enabled to take fresh hold of the latter without being removed therefrom for said purpose. When longer pipe, &c., is to be grasped, the movable jaws separate to a greater extent until the pipe is enabled to enter the recess *c*, and as the biting-face *b* of the stationary jaw extends in a curve from its outer end to the base, it is evident that, as the movable jaw opens to an increased extent, the space between the biting-faces of the jaws proportionately increases, and thus larger pipe, &c., may be introduced, the jaws, however, closing thereon and grasping the same, similar to that first above stated, excepting that the bite of the stationary jaw is exerted farther back.

Having thus described our invention, what we claim as new, and desire to secure by Letters Patent, is—

5 A wrench consisting of a stationary jaw, a handle, a pivotal jaw, coiled springs, and caps, the axial bolt of the pivotal jaw being extended beyond the sides of the stationary jaw, and having said caps attached to its ends, the space between the caps and stationary

jaw receiving said springs, which are secured to the stationary jaw and the axial bolt, substantially as and for the purpose set forth.

FRANK A. SCHRAMM.
AMBROSIUS MODERY.
